Des. 236,881
Patented Sept. 23, 1975

236,881

PACKAGING CONTAINER FOR FILM PROCESSING CHEMICALS

Donald J. Mitchell, St. Paul, Minn., assignor to
Minnesota Mining & Manufacturing Company

Filed Jan. 2, 1974, Ser. No. 429,541

Term of patent 14 years

Int. Cl. D9—03

U.S. Cl. D9—184

FIG. 1

FIG. 2

FIG. 3

FIG. 4

FIG. 5

FIG. 1 is a top plan view of a packaging container for film processing chemicals showing my new design;

FIG. 2 is a front elevation view thereof;

FIG. 3 is a bottom view thereof;

FIG. 4 is a rear elevational view thereof; and

FIG. 5 is a right end view thereof; the left end is a mirror image thereof.

I claim:

The ornamental design for a packaging container for film processing chemicals, substantially as shown and described.
